UNITED STATES PATENT OFFICE.

CHARLES L. STUART, OF OMAHA, NEBRASKA.

COMPOSING-STICK.

1,114,550.

Specification of Letters Patent.

Patented Oct. 20, 1914.

Application filed November 20, 1913. Serial No. 802,122.

To all whom it may concern:

Be it known that I, CHARLES L. STUART, a citizen of the United States, residing at Omaha, in the county of Douglas and State 5 of Nebraska, have invented certain new and useful Improvements in Composing-Sticks; and I do hereby declare the following to be a full, clear, and exact description of the invention, such as will enable others skilled 10 in the art to which it appertains to make and use the same.

This invention relates to improvements in type holding apparatus and more particularly to composing sticks and like devices.

15 The object in view is the quick and easy adjustment of the knee according to the length of line desired. With this and further objects in view, as will in part hereinafter become apparent and in part be 20 stated, the invention comprises certain novel constructions, combinations and arrangements of parts as herein disclosed and claimed.

In the accompanying drawing:—Figure 25 1 is a plan view of an apparatus embodying the features of the present invention. Fig. 2 is an edge view thereof. Fig. 3 is a cross section therethrough taken on the plane indicated by line 3—3 of Fig. 1, and looking 30 in the direction of the arrow.

Referring to the drawing by numerals, 1 indicates a composing stick having the usual bottom 2, side wall 3, and end wall 4. A knee 5 is arranged in the stick 1 and adapted 35 to be slid along the side wall 3, the knee 5 being designed to be wedged into engagement with the side wall by the usual clamp 6, having the pendent flanges 7 and 8, the former extending, when in the locking position, at the inside of one member of knee 5, 40 and the other, at the same time extending on the outside of the side wall 3. The inner face of the side wall 3 is preferably provided along its upper edge with graduations 9, and along its lower edge portion 45 with rack teeth 10—10.

The parts of the angle comprising the knee 5 are connected by a web 11, which is formed with an arcuate slot 12, and a pivot 50 pin extends downwardly from knee 5 and is disposed to have its longitudinal axis the center of the circle of which the arcuate slot 12 is a portion. A lever 14 pivotally engages the pin 13, and extends thence to a 55 point beneath the slot 12, and a set screw 15 extends through the slot and engages the

outer end portion of lever 14 for enabling the manual swinging of the lever by engagement of the said screw 15, the said screw being also formed with an angular 60 flange adapted to engage the upper surface of the web 11 for firmly clamping the lever 14 in any of its adjusted positions. Adjacent the pivot 13, the lever 14 is provided with a mutilated gear 16 disposed to mesh 65 with the rack 10.

In operation, the stick 1 is utilized in the usual manner, and may be positioned for any desired length of line according to the graduations 9. However, if it is desired to have 70 the line of a different length than represented by a given graduation, instead of inserting justifying elements, it is only necessary to release the set screw 15 from its clamped engagement with the web 11 and 75 to shift the same along the slot 12 with a corresponding shifting of lever 14 and a resulting shifting of the knee 5 by the action of the teeth of gear 16 walking along the teeth of the rack 10. By this shifting of 80 the set screw 15, the knee 5 may be adjusted accurately to the one-thousandth of an inch, and the set screw is then again tightened to clamp the lever 14 against movement, whereby the knee 5 is effectively locked in its ad- 85 justed position between the regular points of graduation, or in any position according to the desired length of line.

The invention is obviously susceptible of various modifications, and is well adapted 90 for use on galleys. The simplicity and efficiency of the structure embodying the invention also enhance its value.

What I claim is:—

1. The combination, with a composing 95 stick having a side wall formed with a rack, of a knee coöperating with the stick and movable along the side wall, means for clamping the knee to the side wall, a gear having a journaled connection with the knee 100 and meshing with the rack and adapted to walk along the same for shifting the knee while in engagement with the side wall, a lever for actuating the gear, a slotted web connecting the members of the knee, and 105 means extending through the slot and engaging the lever for locking the same in any of its positions.

2. The combination, with a composing 110 stick having a side wall, of a knee coöperating therewith and adapted to be shifted along the side wall, means for clamping the

knee to the side wall, the knee having a web connecting its angular parts and formed with an arcuate slot, a lever pivoted to the knee, and extending to a point adjacent the web, a set screw extending through the web and engaging the lever and disposed for clamping the lever to the web, and a gear outstanding from the pivoted end of the lever, the side wall of the stick being formed

with a longitudinal rack meshing with said gear.

In testimony whereof I affix my signature in presence of two witnesses.

CHARLES L. STUART.
